UNITED STATES PATENT OFFICE.

ROY F. ENSIGN, OF SOUTH PASADENA, CALIFORNIA, ASSIGNOR TO ENSIGN CARBURETOR COMPANY, OF LOS ANGELES, CALIFORNIA, A CORPORATION OF CALIFORNIA.

CARBURETOR.

Application filed November 30, 1923. Serial No. 677,649.

This discovery and invention involves novel principles in the production of a constant liquid to air ratio.

This invention comprises a Venturi type carburetor having the inherent characteristic of producing a constant fuel to air ratio throughout the entire range of operation of the carburetor, and I have thereby dispensed with the so-called compensating devices such as air bleeds, air valves and auxiliary jets which have heretofore been deemed necessary to accomplish such production.

This discovery and invention is directed toward simplifying the construction and improving the operation of former carburetors; and to the introduction of novel accelerating means, novel economizing means, and novel means for combining a balancing system with a starting system.

An object of this invention is to thin the mixture of fuel and air at moderate or normal loads without involving a like change at higher loads, and I use the depression between the throttle and the engine intake to accomplish this.

The depression beyond the throttle changes according to engine load; a high depression indicates a low load and a low depression a high load and I make use of this changing depression to operate a piston which controls a valve, the opening of which permits the application of the depression existing in the carburetor below the throttle, to the air above the fuel in the fuel supply chamber, thus decreasing the flow of fuel orifice through the fuel.

Some of the objects of this invention are as follows:

To provide novel means whereby separate restrictions of the venturi are used to regulate the atomizing and proportioning of fuel to air;

To provide novel means whereby a carburetor will provide a constant mixture proportion during entire range of operation;

To provide novel and better means for furnishing ample fuel for accelerating purposes.

An object of the invention is to make provision for increasing the flow of fuel through the fuel orifice during acceleration, according to the degree of acceleration.

Another object is to provide a Venturi type carburetor in which the mixing of fuel and

air or atomizing of the fuel by air does not interfere with the proportioning of the fuel to the air passing through the carburetor.

Another object is to provide novel means for changing from normal mixture to a leaner mixture according to the degree of load on the engine.

Heretofore, the majority of carburetors have been provided with a small fuel orifice through which the liquid may flow from the float bowl; and owing to the natural tendency to increase the amount of fuel in proportion to the air whenever the velocity through the carburetor increases, such carburetors do not maintain, over a wide range of pressures, a uniform or constant proportion.

I have made provision to correct such tendency and afford a larger range of flow than heretofore from the constant level chamber to the depression chamber from which the fuel jet discharges into the air stream.

Features of this invention are the provision of a large fuel flow limiting orifice, and a Venturi throat of unusually large area to create the depression which causes the fuel to flow through the fuel orifice; and to bring about the proportioning of the fuel to the air by the depression of the air only at the large throat of the venturi, I admit no fuel from the supply chamber to such large throat, and I impose such depression upon the fuel orifice by action of the air stream through an extra large air passage.

In order to thoroughly mix the fuel and air, I provide a venturi smaller than the proportioning point which creates a greater depression and thus maintains a flow of fuel from the fuel orifice, and air from the proportioning point to the mixing venturi.

I have located the throttle beyond the mixing venturi in order to avoid wide differences in pressure between the mixing venturi and the proportioning point.

Other objects of the invention are simplicity of construction, convenience of manufacture, ease of assembly, and ease with which the carburetor can be adapted to engines of different sizes.

Another feature of the invention lies in a diaphragm arranged below a submerged fuel orifice for the purpose of forcing a sudden increased flow of fuel through such orifice.

Other objects, advantages and features of

invention may appear from the accompanying drawings, the subjoined detail description and the appended claims.

This invention may be carried out by various means and the accompanying drawings illustrate such means and the form of apparatus I at present deem preferable for carrying out the principles of the discovery and invention.

10 Figure 1 is a side elevation of a carburetor constructed in accordance with, and to exemplify this discovery and invention.

Fig. 2 is a horizontal section on line x^2 , Fig. 1.

15 Fig. 3 is a fragmental sectional detail on line x^3 , Fig. 2.

Fig. 4 is a vertical section on line x^4-x^6 , Figs. 2 and 5.

Fig. 6 is an enlarged fragmental sectional detail on line x^4-x^6 , Fig. 2, showing the joint formed with packing.

25 Fig. 7 is a horizontal section of the venturi taken on line x^7 , Figs. 4 and 8.

Fig. 8 is a vertical sectional view on line x^8 , Figs. 2, 9 and 10.

30 Fig. 9 is a horizontal section on line x^9 , Figs. 1, 4, 5 and 8.

Fig. 10 is a broken horizontal section on line x^{10} , Figs. 1, 4, 5 and 8.

The carburetor shell comprises upper and lower sections A, B which are fastened together by a liquid and air tight joint and enclose a Venturi structure C and associated parts.

35 The upper portion A is a single casting comprising a throttle barrel 6, bored out as at 7 to receive an inserted Venturi tube, and flange, as at 8, for connection to an engine intake, and an extension which forms the upper part of a constant level chamber 1 and a depression chamber 3. The partition separating these chambers has a horizontal portion 2, in which is a threaded opening for the sleeve 26, hereinafter described more fully.

40 The lower portion 4 of the depression chamber is hereinafter called a fuel well.

50 The lower section B is conveniently made to include the air intake b, a diaphragm chamber c, and a Venturi seat d, and is connected to the upper section A by means of screws e.

55 The Venturi structure C is adapted to snugly fit into the bore 7 in the piece A below the throttle barrel 6 and is secured therein by a screw 8. The structure C is shown as containing the mixing Venturi throat 11 or the 60 point of maximum air velocity through the carburetor and at which point the fuel is introduced into the main air stream below the upper expanding mouth portion f of the venturi, while the depression chamber 3 is connected with the ports 10 opening into the

venturi at a point, as 9, of greater area than the throat 11, said ports are shown as slots which extend approximately entirely around the venturi at the point 9 and open into a passage 12 between the venturi and the bore 7 of the carburetor body.

Said slots are separated by the connections 13 which prevent separation of the structure. The depression chamber 3 connects with the upper end of the passage 12, to permit the depression effective at the orifices 10 to be also effective in the chamber 3. The lower end 14 of throat 9 flares and forms a stream line approach to the proportioning point 9.

The constant level fuel chamber 1 is supplied with fuel through the usual fuel supply connections 15 and the fuel in said chamber is maintained at a so-called constant level 16 by the usual float 17 and valve 18.

The fuel delivery passage that delivers fuel from the supply chamber 1 to the main air stream thru the Venturi structure for all except very low speeds, comprises the fuel controlling orifice 19, the overflow fuel passage 20, the vertical adjustable ports 21, the fuel well 4, passage 5 and nozzle 24. The passage 5 opens thru a wall of the section A to the bore 22 in the boss 23 that projects from the reduced portion of the Venturi structure. The nozzle 24 fits in the bore 22 and communicates with the main air stream and passage 5.

The part 26 is screwed into the threaded portion 2 and contains the fuel controlling orifice 19 and the bore 2' into which fits the part 20 of the adjusting screw 27.

55 The fuel controlling orifice 19 is below the constant level 16 is normally submerged in the fuel in the supply chamber and admits fuel to the passage 20 from which such fuel is drawn through the vertically adjustable port 21 into the fuel well 4 from which it is drawn through the passage 5 and is discharged from the nozzle 24 into the venturi at the mixing throat 11.

The overflow fuel passage 20 is mounted for vertical adjustment in said part 26, and extends vertically from, and is arranged axially to, the fuel controlling orifice 19. The ports 21 are usually adjusted so that the bottom edge of said ports, will be a predetermined distance from the constant fuel level 16.

60 The passage 5 is preferably extended by a tube 28' and opens at one end into the suction well 4 below the level of the adjustable port 21 and near the bottom of said well 4, and is preferably provided with ports 28.

The space above the fuel in the fuel supply chamber is connected to the air passage in the air intake by means of an equalizer tube 29, one end of which is open toward the inflowing air at the proportioning Venturi throat 9; and the other end of said tube 29 is secured in a bore 30 formed in the Venturi structure C and opens into a passage 31 that communicates with a passage 31' and port 130

K which opens into the fuel supply chamber.

The idling by-pass 32 is connected at its lower end through a passage 38 with an annular chamber 39 formed between the nozzle 5 seat 22 and the delivery end of the nozzle 24, which is reduced to form said annular chamber; the object being to pick up at the end of the nozzle, any fuel which may flow into the venturi when there is not sufficient velocity 10 of air to carry such fuel to the throttle; the depression at this point being from above the throttle, and therefore greater than the depression in the venturi below the throttle.

The idling by-pass 32 is open at its upper 15 end to the throttle bore 6 through the reduced port 33 at a point above the throttle *g*, and such passage opens also into the throttle barrel below the throttle, through the port 34.

The lower end of said by-pass 32 is extended 20 into the depression chamber 3 by means of a tube 35 having a restricted end 36; said tube 35 is inserted through a bore 37. The restricted end 36 is located approximately at a height corresponding with the lower edges of 25 the adjustable overflow ports 21.

The lower end of the by-pass 32 is open to the passage 12 through the passage 38 and a reduced passage 32' in the boss 23 that connects said passage 12 with the passage 38.

Means are provided to apply a depression 30 except at very low speeds, upon the surface of the fuel in the fuel supply chamber, to retard the flow of fuel through the main fuel passage at motor loads about or below one-half to thereby diminish the ratio of fuel to air at such loads to obtain a higher economy during engine operation below half motor load, except at very low speeds. Such means comprise a suction operated piston 42 which 35 is slidably mounted in a bore 43, and divides such bore into upper and lower chambers 44, 45 respectively.

Chamber 44 is open to the throttle barrel above the throttle through the port 46 and the chamber 45 is open below the throttle through the port 47.

A plug 48 is screwed into the upper end of the chamber 44 and has an extension 49 forming a stop to limit the upward movement of the piston. A spring 50 encircling the extension 49 operates between the head of the screw 48 and the piston 42 to force the piston downward against a valve 51 which is loosely mounted in a bore 52, and has a guide 53 extending in the bore to prevent displacement of the valve. Said valve 51 seats on a valve seat 54 and is yieldingly held in seated position by the piston 42 and the spring 50, except when the depression beyond the throttle 55 is sufficient to lift the piston against the pressure of spring 50 when the valve 51 will seat by its own weight except when the depression applied through port 47 is sufficient to raise the valve 51 from its seat.

The lower chamber 45 communicates with

the fuel supply chamber 1 through said bore 52, and passages 55, 55'. The opening of passage 55 may be adjusted by means of a screw 56 threaded into the boss 57 and is locked in adjusted position by the lock nut 58.

70

A choke valve 59 mounted on a shaft 60 controls the air which enters the air intake *b*, and operation of the choke valve 59 also acts to operate a valve to destroy the equalizing effect obtained in the float chamber by the 75 equalizer means 29. This operation is accomplished by the shaft 60 extending through and closing and opening the lower end of the passage 31' which is open at its lower end to the atmosphere preferably through a restricted orifice 31''.

80

When the choke valve 59 is open after the engine has been started, the shaft 60 closes the lower end of the passage 31' and when the choke valve 59 is closed for starting purposes 85 the shaft 60 is oscillated so that a hole 61 in shaft 60 aligns with the passage 31' and thereby opens the lower end of said passage to the atmosphere through the orifice 31'', and thereby increase the pressure upon the 90 surface of the fuel in the fuel supply chamber above that applied by the equalizer means and thus causes a greater flow of fuel through the fuel passage during starting operation.

Means are provided to supply additional 95 fuel for accelerating and comprise a plate 62 which forms the bottom of the fuel supply chamber 1, and is secured between the parts A and B. Said plate 62 is provided directly beneath the fuel orifice 19 with a jet 63. A 100 diaphragm 64 is also secured between the upper and lower pieces A and B and is mounted below the plate 62 in the chamber *c*, which is connected to a point above the throttle by means of a passage 66 having a port 67 at one 105 end and a port 68 at its other end which opens into the throttle barrel above the throttle. A headless screw 66' is forced into the lower end of the passage 66, the purpose of which will be hereinafter explained. An accelerating fuel chamber 65, is formed between the diaphragm 64 and the plate 62.

Suitable packings 69 and 70 are interposed above the plate 62 and between the plate and diaphragm 64 respectively, so as to form an 115 air and gas tight fit between the chamber *c* and the fuel supply chamber 1.

In operation air enters the air intake *b* and flows past the choke valve 59, stream line approach 14, proportioning throat 9, stream 120 line approach 11', mixing throat 11 at which point it receives fuel from the nozzle 24 and the mixture then continues on its way through the upper expanding portion *f* of the venturi past the throttle *g* in the throttle 125 barrel 6 into the engine manifold D.

The depression due to the pumping action of the engine on which is superimposed the depression due to velocity at the proportioning point 9 is applied upon the fuel orifice 19 130

through the elongated slots 10, and air passage 12 thereby applying such depression on the adjustable ports 21 through the depression chamber 3 to cause fuel to flow through the fuel orifice 19.

At idling with the engine throttled so that the suction created by the air velocity through the mixing throat 11 is not sufficient to lift fuel to be delivered to the main air stream through the nozzle 24, fuel is taken from the fuel well 4 through the restricted end 36 of the tube 35 which is an extension of, and communicates with, the by-pass 32 which opens into the throttle barrel 6 above the throttle 9 through the port 33. This is caused by the depression above the throttle being applied to the by-pass 32 through the port 33. The port 34 opening from a point below the throttle into the idling by-pass 26 serves to reduce the suction upon the restricted end of the tube 35.

During low loads the depression in chamber 3 is increased by the connection through the by-pass 32 thus causing an increased flow 23 of fuel through orifice 19 at such loads.

After the velocity of the air through the carburetor increases, the depression at the mixing throat 11 becomes greater and such depression is sufficient at all speeds, except 30 very low speeds, to draw fuel from the fuel well 4 and deliver such fuel to the main air stream from the nozzle 24, as the velocity increases, more and more fuel will be drawn from the well, thereby lowering the height of 35 fuel in the well 4 below the restricted end 36 of the idling by-pass, and thus prevent further delivery of fuel from the well 4 through the idling by-pass until the suction is reduced and the fuel again rises to a level above the restricted end 36 of said by-pass. This emptying and filling of the well 4 supplies additional fuel for accelerating purposes.

As the velocity of the main air stream increases more and more fuel is withdrawn 45 from the fuel well 4 and the ports 28 will be consecutively uncovered thereby admitting more and more air into the well discharge passage to thus regulate and prolong the rate of delivery of fuel from the accelerating well 50 during increase of engine speeds.

Simultaneous with the increase of air velocity at the mixing throat 11 the depression at the proportioning throat 9 is increased and such depression is communicated to the depression chamber 3 and causes an increased flow of fuel from the fuel supply chamber into fuel well 4.

The nozzle 24 is such a small fraction of the area of the slots 10 or the proportioning air 60 passage 12 that the flow of air through the ports 28, passage 5, and nozzle 24 will not materially affect the depression imposed through passage 12 upon the fuel orifice 19 by the pumping action of the engine on which is 65 superimposed the depression due to velocity

at the proportioning point 9 operates to draw fuel into the fuel well 4 at all velocities through the carburetor, thus producing a correct mixture at all engine speeds, while the atomizing is done at the usual velocity and 70 with ample air to produce the atomization.

When the depression applied to the nozzle 24 is sufficient to draw or lift fuel from the well 4, but the velocity of the air stream is not sufficient to carry the fuel onward to the engine manifold, such lifted fuel will be taken from the nozzle 24 and delivered into the throttle barrel beyond the throttle through the annular chamber 39, passage 38, idling by-pass 32, and port 33 by reason of the suction 80 applied to the port 33 during the lower speeds.

In order to equalize or balance the depression applied to the fuel orifice by the friction of the air flow up to the proportioning throat 9 during engine operation, the same depression is applied upon the surface of the fuel in the fuel supply chamber by the suction at the end of the equalizer tube 29 which connects with the fuel supply chamber through the passages 31, 31' and port K.

In order to give high economy I reduce the fuel to air ratio during engine operations with the throttle only slightly open, except at very low speeds. During such range of engine operations the suction above the throttle applies a depression in the chamber 44 through port 46. The piston 42 will be raised against the pressure of the spring 50 releasing the valve 51. The depression below the throttle applies suction to the chamber 45 through the port 47 and when the latter depression is sufficient it raises the valve 51 from its seat 54 thereby opening the passage from the chamber 45 into the fuel supply chamber. The opening of the passage from the chamber 45 into the fuel supply chamber causes an increase in the depression on the surface of the fuel in the fuel chamber and thus reduces the fuel flow through the fuel orifice 19.

The spring 50 is so adjusted that the piston 42 will be raised from idling speeds to approximately half load and thereby permit the valve 51 to be opened during such range of speeds. The valve 51 will be open from approximately half load to approximately one-tenth of the load, when the passage 52 will be closed by the valve 51 due to its own weight because the suction applied to the valve seat in the chamber 45 is not sufficient to hold the valve 51 in open position.

The extension 49 of the screw 48 limits the upward movement of the piston 42 which in turn limits the upward movement of the valve 51.

Adjustment of the screw 56 opens or closes the passage 55, according to the direction said screw is turned and serves to control or adjust the amount of the depression in the 100

float chamber as applied by the equalizer means.

The accelerating fuel chamber 65 is filled with fuel from the constant level fuel supply chamber through the nozzle 63, which is spaced such distance from the fuel orifice 19 as is necessary in order that the filling of the chamber 65 will not affect the flow of fuel from the fuel supply chamber into said orifice. By spacing the fuel jet from the fuel orifice a greater distance than above mentioned, the flow of fuel for acceleration may be regulated. When a suction or depression is applied to the port 68, as for example, during the lower speeds with the throttle partially closed, a like depression is applied through the passage 66 and port 67 to the chamber *c*, underneath the diaphragm 64, and this draws the diaphragm downward until it contacts with the bottom wall *m* of the chamber *c*, thereby preventing fluttering of the diaphragm and consequent forcing of fuel from the jet 63. By thus drawing the diaphragm downward, the capacity of the accelerating fuel chamber 65 is increased and such increase is supplied by fuel from the fuel supply chamber so that additional fuel for acceleration is accumulated and stored for use.

30 The flow of air in the passage 66 to and from the chamber *c* takes a spiral path around the threads of the screw 66' thus retarding the air flow in the passage 66 to prevent a fluttering of the diaphragm 64.

35 When the depression at the port 68 is decreased, as for example, when the throttle is suddenly opened, the result is that the suction holding the diaphragm down is removed and the diaphragm will return by its own 40 resiliency to normal position and cause fuel accumulated in chamber 65 to be projected into the supply chamber from the jet 63 directly toward the fuel orifice 19, with such impulse as to effect an increase of fuel flow 45 through the fuel orifice 19 during accelerating periods, without any positive pumping of fuel through such fuel orifice 19. In other words the stream of fuel forced from jet 63 into orifice 19 entrains fuel from the constant level fuel chamber into the fuel passage 50 thereby effecting an increase of fuel flow through the fuel orifice 19 during accelerating periods.

I claim.

55 1. In a carburetor comprising a fuel supply chamber, and an air intake, a shaft mounted in said air intake; a choke valve mounted upon said shaft; a fuel orifice; means to deliver fuel from said fuel supply 60 chamber through said orifice to the air stream; means to equalize the depression

caused by air resistance which would otherwise add to the flow of fuel through said fuel orifice; and means controlled by operation of the choke valve to destroy the effect of the 65 equalizer means to cause an increased flow of fuel through the fuel orifice during starting operation.

2. A carburetor comprising a fuel supply chamber, a fuel passage connected to deliver 70 fuel from the fuel supply chamber into the main air stream and comprising a fuel orifice opening into said fuel chamber; a throttle to control the flow of said air stream; a plate having a fuel jet spaced from and co-axial 75 with said fuel orifice; a chamber; a diaphragm mounted in said chamber and forming an accelerating well between said diaphragm and said plate, said accelerating well being adapted to accumulate fuel from the 80 fuel supply chamber through said jet; and a passage connecting the chamber below the diaphragm to the air stream above the throttle to apply a depression in said chamber to hold the diaphragm down when such depression is applied, and to release said diaphragm when the depression is removed to force fuel through said jet into said fuel supply chamber to cause additional fuel flow through said 85 fuel orifice.

3. A carburetor comprising a mixing throat, a throttle, a throttle barrel, and a fuel supply chamber, a fuel passage from said supply chamber to said mixing throat; a passage connecting said supply chamber with the throttle barrel below the throttle; a valve controlling said passage; and means operable by the depression above the throttle to permit said valve to open.

4. In a carburetor comprising a fuel supply chamber, a fuel delivery passage adapted to deliver fuel from said supply chamber to the mixture passage; a throttle to control the mixture passage; an upper chamber connected to the mixture passage by a port above the throttle; a piston in said chamber adapted to be raised against resistance by a depression applied to said port; a lower chamber connected to the mixture passage through another port below the throttle; a passage connecting said lower chamber with the supply chamber; a valve in said lower chamber adapted to close said passage and also adapted to be raised by a depression applied thereto through said other port only when 105 said piston is raised and to close the passage when the depression thereon is insufficient to hold the valve open.

In testimony whereof, I have hereunto set my hand at Los Angeles, California, this 23rd 110 day of November, 1923.

ROY F. ENSIGN.
